UNITED STATES PATENT OFFICE.

FRANK W. OFELDT, OF NEWARK, NEW JERSEY.

HYDROCARBON-FURNACE FOR STEAM-BOILERS.

SPECIFICATION forming part of Letters Patent No. 393,850, dated December 4, 1888.

Application filed June 9, 1887. Serial No. 240,686. (No model.)

To all whom it may concern:

Be it known that I, FRANK W. OFELDT, of Newark, in the county of Essex and State of New Jersey, have invented certain new and useful Improvements in Hydrocarbon-Furnaces for Steam-Boilers; and I do hereby declare that the following is a full and exact description thereof, reference being had to the accompanying drawings, and to the letters of reference marked thereon, making a part of this specification, in which—

Figure 1 is a central vertical section through my improved furnace as applied to a steam-boiler, with a portion of the encircling heating-coils of the latter removed and showing the oil-pump in elevation. Fig. 2 is an irregular horizontal section in line $x-x$ of Fig. 1, illustrating the arrangement of burners projecting radially from the gas-chamber; Fig. 3, a horizontal section in line $y-y$ of Fig. 1; Fig. 4, a detached sectional view illustrating the improved coupling by which the heating-coils are connected to the central-drum, and Fig. 5 is a detail view in elevation of a modification of the means for operating the piston of the oil-pump.

My invention, which relates to a combination of devices for effectually promoting the heating and evaporation of water by means of the vapor of naphtha admixed with air, has for its object to obtain a steady uniform pressure in the furnace and the exposure to the heat thereof of the greatest possible extent of water-heating surface within the least area.

It consists in the combination, with a series of burner-tubes by preference arranged to radiate in a common horizontal plane from a central supply and pressure chamber, and with an injector by which said chamber is supplied with an inflammable compound of vaporized naphtha and air, of a pump whose piston is drawn outward (so as to charge the cylinder with naphtha) by a coupling-rod connecting it positively with the engine, but is freed from said coupling-rod on the return-stroke, and is forced inward (to feed the naphtha to the injector) by means of a spring or weight.

It consists, second, in combining a length of the feed-tube supplying the injector and also the tube connecting the injector and the burners with the furnace, so that said tube

shall be subjected to the heat of the burners, whereby the naphtha becomes vaporized as it approaches the injector and the admixture of 55 the vapor, and air is heated before entering the burners.

My invention further consists in the details of construction and combination of parts, as will be more fully described, and pointed out 60 in the claims.

In the accompanying drawings, A represents a metallic cylinder or water-drum, preferably of sheet-steel, screwed with a tight joint at its lower end into a casting, B, forming a continuation thereof, but which is divided transversely by a partition, C, into an upper and a lower compartment. The upper compartment of this casting B forms the bottom of the water-drum, and the lower compartment forms a closed chamber, D.

A series of gas-tubes, W W, closed at their outer ends, are secured radially in the same horizontal plane into the wall of the chamber D, just below the partition C, to communicate 75 with said chamber, and these radial tubes are properly perforated in their upper sides with a series of jet-openings to serve as gas-burners.

A series of small independent tubular coils, T T, are arranged vertically and concentrically around the water-drum A, and are each coupled separately thereto to communicate freely at each end thereof with the interior of said drum. The lower ends of these circulating tubes or coils T T are coupled to the 85 drum just above its connection with the casting B, and consequently but a little distance above the bottom of the drum, and the coils are of such length as that their upper ends are coupled to the drum at about two-thirds 90 (more or less) its length from said lower end, leaving a steam-space, A', in the drum above the upper ends of the coils. A water-supply pipe, S, is connected to the lower end of the drum, and the top of the drum is closed and 95 fitted with a steam-eduction pipe, S', which is preferably made to return in a coil about the upper end of the drum down to just above the level of the upper ends of the circulating coils to operate as a superheater for the steam 100 before it is carried outward from the boiler.

The coupling of each end of the several coils T T to the drum is effected by means of a coupling sleeve or bushing, E, (see Fig. 4,) 100

adapted to screw closely with a tight joint into a threaded aperture in the wall of the drum. This bushing E is internally as well as externally threaded, the two threads being, 5 however, cut in opposite directions. The ends of each coil are also threaded to enter and fit in the bushing, so that by entering the end of the coil into the bushing and the bushing into the threaded aperture in the drum, and 10 turning the bushing in the proper direction, the two joints will be simultaneously made by the operation of the right and left screws and a close tight connection of the tube and drum be thereby effected. The joint may in 15 like manner be readily broken, permitting any one of the coils to be easily removed or replaced without disturbing the others.

The central drum, A, circulating-coils T T, superheating-coils S', and radial burners W 20 W are all inclosed by an outer shell or case, F, in the customary manner, said casing serving as a furnace, concentrating the heat from the burners upon the drum and coils of the boiler.

25 An air-supply pipe, G, is carried from a point near the top of the furnace, at which it communicates freely through the shell or case F with the outer air down within the furnace to connect with the gas-chamber D. A vertical 30 stand-pipe, H, of about the same diameter as the air-pipe G, is mounted parallel therewith within the furnace, and is connected by a small supply-tube, L, at its lower end with the cylinder J of an oil-pump, and at its upper 35 end with a small injector-pipe, K, whose nozzle is inserted into the upper end of the air-pipe G, so as to form in combination therewith an injector of simple form, as shown in Fig. 1.

40 The air-pipe G, oil-pipe H, and injector K are all exposed to the full heat of the furnace.

The oil-pump is connected with a tank or reservoir, P, of naphtha. Its piston is driven inward to force the oil out of the cylinder into 45 the pipe L by means of a weight, M, (see Fig. 1,) or a spring, N, (see Fig. 5,) as its equivalent, and is drawn out again to cause an inflow of oil from the reservoir into the cylinder by means of a coupling-rod, R, or other equivalent device made to reciprocate by a suitable 50 motor, the connection of the coupling-rod to the piston being made by means of an extended slot, as shown at R'. By this means, whatever may be the force with which the 55 piston is drawn out or the rapidity of its movement, the force and pressure of the piston in driving the oil out of the cylinder is at all times equal and uniform, being determined by the gravity of the weight M or power of 60 the spring N, and its inward movement is determined by the resistance in the pipe L.

The arrangement and combination of the 65 series of small independent spiral coils disposed vertically each at one side of the main central water-drum, with which they communicate freely at each end, permits the largest possible amount of heating-surface to be ob-

tained within a minimum of space under such conditions as will utilize to the utmost the heat from the burners and produce and maintain the utmost freedom of circulation through 70 the tubes and drum.

In the use and operation of my improved apparatus the water in the drum A may be kept at any desired level, but preferably about 75 midway between the ends of the encircling coils. In starting the furnace a small supply of naphtha may be injected into the tubes G H and gas-chamber D by operating the pump by hand, and the vapor, lighted as it 80 issues from the burners W W, will speedily so heat the tubes as to produce the requisite flow of gas to the burners for their full supply. As the oil, fed with the constant pressure of the weight M, flows from the tube L 85 into the larger stand-pipe, H, it is vaporized therein by the heat thereof, and will issue in a strong jet through the nozzle of the injector K into the air-pipe G and create a strong current therein, whereby a large proportion of 90 atmospheric air will be admixed with the hot naphtha-vapor, producing a highly inflammable compound, which in passing through the hot pipe G will enter in this condition the gas-chamber D, and be thence delivered 95 equally to the several radiating burners W W W. The intense heat from these burners will not only superheat the tubes G and H, supplying the burners, but will be brought to bear with full force upon the series of small 100 tubular coils T T and the central drum, so as to produce a most rapid evaporation of the water and a large volume of steam to be delivered through the pipe S'.

I claim as my invention—

1. In a steam-generator, the combination, with a boiler having a series of water-tubes and burners located below the tubes, of the oil-feeding tube for supplying the burners, the pump for charging the tube, mechanism 110 actuated by the engine and operating to draw the pump-piston outwardly only, the said piston being constructed and arranged to be moved downwardly, and thereby drive the oil into the feed-tube with a constant pressure, the above parts being constructed and arranged substantially as shown and described.

2. In a steam-generator, the combination, with the boiler having a series of water-tubes and the series of burners below the tubes, of the oil-pump for supplying the burners, the oil-feeding tube fitted within the furnace and located over and exposed to the direct heat of the burner, and the second pipe open to the 120 outer air and extending from the oil-feeding tube to the burners wholly within the furnace, substantially as set forth.

3. In a steam-generator, the combination, with the furnace having the central water-drum, and the series of small independent coils disposed vertically in concentric rows about the central drum and coupled thereto at each end, each wholly upon one side of the

drum, of the vapor-chamber below the stand-pipe, burner-tubes leading from said chamber, the pump for supplying oil, and the combined air and vapor supply pipe leading to 5 said vapor-chamber, substantially as set forth.

4. In a steam-generator, the combination, with a central drum having a transverse partition dividing the drum into two parts, burner-tubes leading from the drum at a point below 10 the partition, independent tubular coils attached at their ends to the drum at a point above the partition, an outer casing and a water-tube leading to the drum, and a steam-pipe

leading therefrom at a point above the partition, of a vapor-pipe leading to the drum at a 15 point below the partition, a pipe leading to said vapor-pipe, and pump for forcing oil into said pipe, the above parts being constructed and arranged substantially as set forth.

In testimony whereof I have signed my name 20 to this specification in the presence of two subscribing witnesses.

FRANK W. OFELDT.
